Specification for Design.

Patented Oct. 4, 1921.

Application filed September 23, 1920. Serial No. 412,403. Term of patent 14 years.

To all whom it may concern:

Be it known that I, LOUIS A. WEGENAAR, a citizen of the United States, residing at Brooklyn, in the county of Kings and State of New York, have invented a new, original, and ornamental Design for a Receptacle for Toilet Powder and other Commodities, of which the following is a specification, reference being had to the accompanying drawing, forming part thereof.

Fig. 2 is a top plan view of Fig. 1.

I claim:

The ornamental design for a receptacle for toilet powder and other commodities substantially as shown.

LOUIS A. WEGENAAR.
